PORATION OF OHIO

METAL SHEETING

Application filed November 4, 1927. Serial No. 230,991.

Our invention relates to metal sheeting and has to do with the provision of a novel form of sheeting and a novel method of and apparatus for attaching such sheeting to the 5 framework of a building or other structure.

We have provided a sheeting structure made up of separate sheets of such cross-sectional design that a roof or other surface formed from a plurality of such sheets will 10 be capable of carrying a greater load per square foot than a roof or other surface covered with ordinary types of sheeting. Furthermore, the construction of the edges of each of the sheets and the construction of the 15 joining structure for these edges is such that the juncture of any two sheets will be as strong if not stronger than any other part of such sheets.

Our sheeting is so constructed that it is 20 possible to nest or lap the sheets with sufficient exactness to prevent leakage, under any circumstances, without the necessity of special flashing or the use of closing devices at the 25 end laps. Also, our sheeting is constructed so that the separate sheets may be attached together at as many points as is desirable, while the attaching mechanism is of a nature that will permit the sheeting to be taken 30 apart and removed at any time without difficulty or injury to the sheeting.

The attaching mechanism for such sheeting avoids the use of fastening means, such as 35 nails or the like, that perforate the metal and is of such nature that the fastening means can be caused to grip and even indent the sheet so as to obviate slippage of the fastening means and of the sheeting as well. The respective sheets have their edges so constructed and the fastening means are so 40 formed complementally, as to prevent any lateral movement of the separate sheets after they are secured together by the fastening means and the fastening means are inherently 45 constructed so as to prevent any possibility of vertical or lateral movement of the fastening means itself.

Our invention is fully set forth in the following detailed description and is illustrated 50 in the accompanying drawings wherein simi-

lar characters of reference designate corresponding parts and wherein:

Figure 1 is a perspective view showing the novel manner of forming the joints between adjacent sheets. 55

Figure 2 is a side view of the joint shown in Figure 1 showing the securing clamp both in inoperative and securing position.

Figure 3 is a perspective view showing the novel manner of forming the joints between adjacent sheets with a modified form of securing clamp. 60

Figure 4 is a side view of the joint shown in Figure 3 showing the modified form of securing clamp in both inoperative and securing position. 65

Figure 5 is a perspective view showing the novel manner of forming the joints between adjacent sheets with still another modified form of securing clamp. 70

Figure 6 is a side view of the joint shown in Figure 5 showing the securing clamp in both inoperative and securing position.

Figure 7 is a perspective view showing the novel manner of forming the joints between adjacent sheets and the type of securing clamp used in attaching the sheeting to the purlins of a building or other structure. 75

Figure 8 is a side view, partly in section, 80 of the joint shown in Figure 7 showing the securing clamp fastened to the purlin.

Figure 9 is a perspective view of the novel manner of forming the joint between adjacent sheets when using a modified form of 85 cap strip.

Figure 10 is a side view of the joint shown in Figure 9 showing the securing clamp in both inoperative and securing position.

Figure 11 is a perspective view of the novel manner of forming the joints between adjacent sheets showing the method of fastening the sheets when a cap strip is not used. 90

Figure 12 is a side view of the joint shown in Figure 11 showing the securing clamp in 95 both inoperative and securing position.

With reference to the drawings, we have shown the preferred form of our invention as embodying separate sheets 1. These sheets may be of any desired size and shape but are, 100

preferably, rectangular and may be provided with one or more ribs or corrugations intermediate the opposite edges of each sheet. The opposite edges of each of the separate sheets are turned upwardly and downwardly to form a rib 2 and then upwardly to form a gutter 2^a. A cap strip 3 is provided to cooperate with the suitably spaced edges of adjacent sheets and each cap strip is preferably provided with leg portions 4 and angular portions 5 which are adapted to fit the similarly shaped edges of the sheets. The cap strips 3 may be of any desired cross-sectional shape and different shapes are shown in Figures 1 and 9.

To secure the cap strip in position after it has been assembled with the adjacent edges of two separate sheets, an H-shaped clamp 6 is provided and, as clearly shown in Figure 1, the projecting portions 7 thereof hook over the tops of the angular portions 5 of the cap strip and hold them in nested relation with the ribs 2 at the same time the projecting portion 8 of the clamp engages the bottoms 25 of the sheets of the gutter 2^a of the adjacent sheets 1. As clearly shown in Figure 2, the clamp 6 may be crimped or bent as at 9, so projecting that the portions 7 and 8 thereof will indent the metal and tightly secure the sheets in position.

This method of securing the sheets together obviates the necessity for punching indexed holes in the sheeting and in the cap strip and provides a rigid assembly, at the same time permitting the sheets to be readily disassembled without difficulty or damage to the sheets. It will be noted that the bottoms of the gutters 2^a of the sheets 1 are in the same plane as the body of the sheets and, therefore, support part of the weight which would, otherwise, be supported by the intermediate part of the sheet.

With reference to Figure 3 of the drawings, I have shown a modified form of securing clamp 10 wherein the lower projecting portion 11 of the securing clamp is provided with laterally extending portions 12. The purpose of these extending portions is shown in Figure 4. With reference to this figure, it will be apparent that, when the securing clamp 10 is bent as at 13, the laterally extending portions 12 will be moved upwardly to engage the sides of the gutters 2^a of the sheets 1 on one side of their outer surface. The extending portions 12 engaging the gutters 2^a of the sheets 1, on their respective outer surfaces and the opposite sides of the gutters 2^a bearing against the opposite sides 60 of the securing clamp 10 at the shank thereof, together with the upper projecting portion 14 contacting with the upper part of the angular portions 5 of the cap strip, will obviate any possibility of lateral movement 65 of the separate sheets after they have been

assembled with the cap strips and securing clamp.

Referring to Figure 5, we have shown another modification of our securing clamp. In this figure, the lower projecting portion 15 on the securing clamp 16 has the portions 17 thereon which extend outwardly from the top thereof. These outwardly extending portions are adapted to engage the outer sides of the respective gutters 2^a of the sheets 1 when the securing clamp is bent as shown in Figure 6 and serve the same purpose as the outwardly extending portions 12 hereinbefore described.

Some of the securing clamps may be constructed in the manner shown in Figure 7 wherein the clamp 18 is provided with an extension 19 which may be secured to the supporting framework or purlin in any desired manner and serves to hold the sheets in proper position with relation to such supporting framework or purlin. As shown in Figure 8, the extending portion 19 of the securing clamp 18 is bent around the purlin 20 in such a manner as to hold the sheets securely to the purlin and to prevent vertical or longitudinal movement of the sheets.

In Figure 9 of the drawings, we have shown a modified form of cap strip in which the legs 21 do not take the same angular shape as the opposite edges of the sheets. Such structure is provided in order that the cap strips may be added after the sheets are assembled if desired. In this instance, the first upward extension of the sheets 1 are used as a flashing to prevent leakage through the joints. If, in this instance, there should be any leakage between the cap strip and the sheets, as a result of capillary attraction, the water which has leaked through will be carried away by the gutters 2^a along the adjacent edges of the sheets. It will be clearly understood that the leakage, due to capillary attraction, will seldom, if ever, reach such a degree that the gutters 2^a will not be able to carry away the water with ease. The gutters 2^a are found in all of the structures and serve the same purpose therein.

In Figure 11 of the drawings, we have shown a joint between adjacent edges of separate sheets as being formed without the use of a cap strip. Such construction is seldom used but when it is used, the downwardly depending portions 23 of the upper projecting portion 7 on the securing clamp 6 will prevent lateral movement of the sheets by engaging the first upwardly extending portion of the sheets.

From the preceding description it will be apparent that we have provided a metal sheeting which may be adapted to innumerable uses and which is so constructed that it may be quickly and easily applied with the use of simple tools, such as pliers or the like, to form a substantial structure which may be

readily disassembled without injury to the sheeting.

It will also be apparent that we have provided a sheeting structure in which the separate sheets will be held securely against lateral movement after they have been assembled. Furthermore, the joints between the sheets are so constructed as to provide a means for carrying away any water that might possibly seep through the joints as a result of capillary attraction and obviate the necessity of special flashing.

Having thus described our invention, what we claim is:

- 15 1. A fastening device for the adjacent edges of panels comprising a shank, laterally extending hook-like wings on said shank, laterally extending wings spaced therefrom, said last named wings having flange members constructed and mounted to prevent lateral movement of adjacent panels when said shank is bent.
- 20 2. A fastening device for sheeting comprising a body portion, laterally extending wings, and portions extending outwardly in angular relation to said wings, said portions being constructed and located to prevent lateral movement of the sheeting when the fastening device is bent.
- 25 30 In testimony whereof we herewith affix our signatures.
